COMPRESSOR OR PUMP

Harvey W. Bell, Yonkers, N. Y.

Application October 19, 1944, Serial No. 559,361

13 Claims. (Cl. 230—21)

1

The present invention relates to compressors or pumps, and more particularly to the means for varying their effective volumetric displacement or capacity.

It is desirable that compressors for certain purposes be provided with means for varying their effective displacement. For example, such displacement varying means may be advantageous where the compressor is intended to provide motive air or other gases under pressure to a gas motor in a power generating and transmitting system, such as that shown in my co-pending application Serial No. 497,781, now abandoned, or is intended to serve as a power amplifying torque converter. In such compressors, if variations in volumetric displacement are to be accomplished by means of an unloading valve operable to render ineffective a selected portion of the compression stroke, then the clearance space in the compressor presents a problem. If this unloading valve is prematurely opened during the initial stages of the suction stroke, the air compressed in the clearance space during the compression stroke is released through said valve during the suction stroke, so that a portion of the work of compression will be lost. This clearance loss increases as the pressure ratio is increased.

It is also important that for any one final pressure, the ratios of effective displacements of the different cylinders in a multi-stage compressor be maintained substantially constant with changes in these effective displacements, and that the ratio be such as to substantially equalize the work and heat generated in the cylinders. For example, if the compressor is two-stage and is designed to compress air to a final pressure of 220 lbs. gage at sea level, then the displacement of the low pressure cylinder should be about four times that of the high pressure cylinder, or the ratio of compression in each cylinder should be about four. This ratio of compression in each cylinder and the ratio of displacements of the two cylinders should be maintained with variations in the output of the compressor.

One object of the present invention is to provide a compressor having new and improved means for varying its effective displacement or capacity.

Another object is to provide a compressor having comparatively simple but, nevertheless, effective means for varying by infinite increments its effective displacement.

A further object is to provide a multi-stage compressor having means for varying the effec-

5 tive displacement of the cylinders of its different stages simultaneously.

Another object is to provide new and improved compressor features which vary the effective displacement or capacity of the compressor, and which may be employed to vary the output of a single or multi-stage compressor.

Another object is to provide new and improved compressor features which vary the effective displacement or capacity of a compressor, and which are operable for manual or automatic control.

Another object is to provide new and improved compressor features which vary the effective displacement or capacity of a compressor, and which may be employed to maintain automatically a nearly constant pressure in a receiver or storage tank of a system in which the demand for compressed air varies, without varying the speed of the compressor or subjecting it to shock as a result of a sudden change in the load.

Another object is to provide new and improved means which vary the effective displacement or capacity of a compressor, and which may be employed to equalize the work of compression of the different stages of a multi-stage compressor for different final pressures. In carrying out this object of the invention, the cylinders of a multi-stage compressor may be correctly proportioned for one final pressure, and the compressor may be efficiently employed for a greater or lesser final pressure by adjusting the mechanism to proportion correctly the effective displacements of the different cylinders of the different stages for the new final pressure. The same multi-stage compressor may be efficiently employed for the same or a different gage pressure at different altitudes by adjustment of the control of the effective displacements of the different cylinders of the different stages for equalization of the work of the stages.

Another object is to provide new and improved means which vary the effective displacement or capacity of a compressor, and which may be employed in connection with a prime mover, such as an internal combustion engine, to compress and deliver air in infinitely variable ratios of volume and pressure. In carrying out this object of the present invention, the power of the engine may be employed to compress and deliver air at a relatively high pressure, but in relatively small volumes, or may be employed to compress and deliver a greater volume of air at a lower pressure. This feature makes possible a pneumatic torque converter somewhat as the variable stroke hy-

draulic pump makes possible the hydraulic torque converter. With this feature, the power of the prime mover may be employed to supply a relatively large volume of relatively low pressure air to an air motor to drive it at high speed when the torque requirement is low, or the power of the prime mover may be employed to supply air at a relatively high pressure, but in small volumes, to drive an air motor when the torque requirement is high.

A further object is to provide new and improved compressor features which vary the effective displacement or capacity of a compressor, and which are arranged to permit rotation of the crankshaft of a compressor in either direction without its effective displacement being altered for any adjustment of its control member.

In accordance with certain features of the present invention, the cylinder of the compressor, whether it is of the single stage or multi-stage type, has an unloading valve which is positively maintained by a mechanical device in open position from the beginning of the compression stroke to a selected phase of said stroke prior to the opening of the discharge or delivery valve. As far as certain aspects of the present invention are concerned, this unloading valve may be the only inlet suction valve of the cylinder, or may be provided in addition to the ordinary inlet valve. While this unloading valve is open, air cannot be compressed in the cylinder and compression cannot begin until this valve is closed. This valve is initially opened during the final stages of the suction stroke, and is maintained open during the initial stages of the compression stroke, according to the setting of the valve control means. Means are provided for adjusting the phasing of the opening and closing of the unloading valve with respect to the stroke cycle of the piston. This adjustment is desirably so effected that the point in the suction stroke when the valve opens (as measured from the end of the suction stroke) corresponds to the phase in the compression stroke when said valve closes (as measured from the beginning of the compression stroke). For example, when the compressor is running with its displacement 100% effective, there is no mechanical opening or closing of the unloading valve; at 50% displacement, it would be opened approximately at midsection of the suction stroke if suction has not previously opened it and closed at midsection of the compression stroke; at one-third capacity, the unloading valve is opened during the suction stroke after the piston has travelled approximately one-third of said stroke, and is closed after traveling two-thirds of its compression stroke; and at zero displacement, it is open throughout the whole of the suction and compression strokes.

The unloading valve is so operated that, with any adjustment of its control, it remains closed during the suction stroke until the pressure of the air in the cylinder is less than the pressure of the air in the inlet pipe. Therefore, at the end of the compression stroke, any compressed air in the clearance space will be reexpanded against the piston, and will not be released through the unloading valve. The work of compressing this air in the clearance space is thereby returned to the piston and will not be lost.

As a further feature, in one of the embodiments of the invention, the means for varying the displacement of the compressor cylinder is automatically operated to maintain the pressure

at the delivery end of the compressor or in a receiver substantially constant, at any desired pressure.

As another feature of the present invention, the mechanical means for operating the unloading valves in the different cylinders of a multi-stage compressor are interconnected and adjusted from a single control in such a manner that the effective displacements of the cylinders of the different stages are varied alike so that the ratio of compression of the different stages is not varied with different compressor outputs, provided the final pressure remains the same.

Due to the fact that under certain conditions some of the air which is taken into the cylinders is discharged therefrom before compression starts, effective internal cooling of the cylinder and valves is obtained.

Various other objects, features and advantages of the invention will be apparent from the following particular description, and from an inspection of the accompanying drawings, in which:

Fig. 1 is a vertical section of a two-stage single-acting compressor taken on the line 1—1 of Fig. 6 through the low pressure cylinder, and embodying certain features of the present invention;

Fig. 2 is a vertical section of the compressor taken axially through the high pressure cylinder on the line 2—2 of Fig. 6;

Fig. 3 is a horizontal section of the compressor taken on line 3—3 of Fig. 2;

Fig. 4 is a vertical section of the compressor taken on line 4—4 of Fig. 2, and showing the working portion of said compressor;

Fig. 5 is a section of the control means for varying the effective displacement of the compressor cylinders taken on line 5—5 of Fig. 2, and constituting a continuation at the right hand end of Fig. 4;

Fig. 6 is a horizontal section of the compressor taken along line 6—6 of Fig. 1, and showing the working parts of the compressor;

Fig. 8 is a side elevation of the cam and follower device for controlling the effective displacement of the low pressure cylinder;

Figs. 9, 10, 11, 12, 13 and 14 are sections taken along the lines 9—9, 10—10, 11—11, 12—12, 13—13 and 14—14 respectively of Fig. 8;

Fig. 15 is a top plan view somewhat diagrammatic showing a general arrangement of a two-stage compressor with its intercooler and pipe connections;

Fig. 16 is a top plan view of a multi-cylinder two stage compressor of the present invention provided with a single intercooler;

Fig. 17 is a top plan view somewhat diagrammatic showing a multi-cylinder two-stage compressor of the present invention having a common outlet, but having more than one intercooler, and

Fig. 18 is a vertical section, somewhat diagrammatic showing the present invention embodied in a double acting compressor.

The present invention is shown in Figs. 1—15 for the purpose of illustration, embodied in a two-stage single-acting compressor 10 in which the low pressure cylinder 11 and the high pressure cylinder 12 are vertically arranged in line. The air or other gas to be compressed is compressed to a certain pressure in the low pressure cylinder 11, passes to an intercooler 13 (Fig. 15) in which its temperature is reduced, and finally enters the

high pressure cylinder 12 where it is compressed to a higher pressure.

The compressor 10 comprises a casting 11 secured at its lower end to a crankcase 16 by screws or bolts 16a. The crankcase sets upon a base 16b and is secured thereto by screws or bolts 16c. The casting 10 has the necessary bores to define the two adjoining cylinders 11 and 12. The head end of the low pressure cylinder 11 is provided with a removable head 17 constituting a water jacket (Fig. 1) having an inlet 18 and an outlet 20 for the circulating cooling water. The high pressure cylinder 12 is similarly provided with a head 21 also in the form of a jacket (Fig. 2) with inlet and outlet connections 22 and 23 for the circulating water. Radiating ribs 24 on the two cylinders 11 and 12 serve to abstract further the heat of compression from the air.

Reciprocable in the low pressure cylinder 11 is a piston 27 pivotally attached in the usual manner to one end of a connecting rod 28, the other end being pivotally secured to a crank 30, affixed to a crank shaft 31 journaled in split bearings 31a in the crankcase 16, and in bearings 31b of end plates 31c secured to the opposite ends of the casing 16. The high pressure cylinder 12 is similarly provided with a piston 32 driven in the usual manner from the crank shaft 31 by means of a crank 33 on said crank shaft, and a connecting rod 34 between said crank and said piston. Counter-weights 35 and 36 on the cranks 30 and 33, and a fly wheel 37 (Fig. 4) on the crank shaft 31 serve their usual counterbalancing and speed equalizing function.

The two cranks 30 and 33 are shown 180° apart on the crank shaft 31, so that while one piston is undergoing its suction stroke, the other piston is traveling in the direction of its compression stroke.

The driving power for the crank shaft 31 is derived from any suitable source, such as a steam engine or electric or gas motor which may be connected to one end of the crank shaft 31.

The air or other gas from the atmosphere or other source, passes through a filter 40 and into the inlet port 41 of the low pressure cylinder 11 (Figs. 3, 4 and 15). This inlet port 41 leads into one side of the working end of the low pressure cylinder 11 opposite to and near the lower end of its head or water jacket 17, and is controlled by an inlet valve 42 of any well known construction. This inlet valve 42 is shown, for the purpose of illustration, of the usual thin-plate type.

Leading from one side of the working end of the low pressure cylinder 11 alongside head 17 near its lower end is a discharge port 43 (Fig. 3) connected to the inlet of the intercooler 13 through a pipe 44 (see Fig. 15 also), and controlled by a discharge valve 45, shown for the purposes of illustration of the usual thin-plate type. This discharge port 43 is circumferentially spaced about 90° from the inlet port 41.

The two valves 42 and 45 each have a plurality of springs pressing against the valve plate so as to be automatically operable in accordance with the pressure in the cylinder 11. During the downward suction stroke of the piston 27, the inlet valve 42 is automatically opened to permit the induction of air by suction therein, and during the upward compression stroke, the inlet valve 42 is closed by the pressure of the air in the cylinder 11, and by its springs and when said pressure slightly exceeds the pressure in the outlet pipe, the valve 45 is automatically opened against the action of its spring or springs. The compressed

air is thereupon discharged from the cylinder 11, through the pipe 44 and into the inlet of the intercooler 13.

The air from the outlet of the intercooler 13 is delivered by a pipe 47, see again Figs. 3 and 15, to an inlet port 48 of the high pressure cylinder 12. This inlet port 48 communicates with an inlet valve 50 and an unloading valve 82 to be described. An outlet valve 52 in discharge port 54 is located opposite unloading valve 82 in cylinder 12.

The operation of the high pressure stage of the compressor is similar to that described in connection with the low pressure stage. The discharge valve 52 permits the passage of the air through a pipe 52a into a receiver 53 from which it may be conducted, through a valve controlled pipe 54, to be used as desired.

As a feature of the present invention, means

20 are provided for controlling the effective displacements of the two cylinders in the proper proportions to maintain the ratios of these displacements substantially equal. The means for controlling the effective displacement of the low pressure cylinder 11 comprises an unloading port 55 (Figs. 3 and 15) in the side of said cylinder diametrically opposite the discharge port 43, and communicating with the inlet port 41 through an arcuate passageway 56 extending around said cylinder. An unloading valve 57 in the port 55 and shown of the poppet mushroom type, comprises a conical disc 58 adapted to cooperate with a conical valve seat 60 in the wall of the cylinder 11. Rigid with the valve disc 58 is a stem 61 supported for axial movement in a slide bearing 62 forming part of a valve housing 63. This bearing 62 has a flange 64 forming one wall of the housing 63, and secured to the casting 15 by studs 65. The depending section of this flange 64 may be provided with a series of radiating ribs 66. Forming the other part of the valve housing 63 and connected to the flange 64 and to the casting 15 by the studs 65 is a housing section 67.

30 The valve 57 is normally maintained in the closed position shown in Fig. 3 by means of a coil spring 68 in the housing 63 encircling the valve stem 61, and bearing at one end against the fixed bearing 62, and at the other end against an abutment collar 70 affixed to the outer end of said valve stem.

35 The valve 57 is maintained in open position by means of a rocker arm 71 disposed in the housing 63 and secured at one end to a rocker shaft 72 journaled in the housing section 67. The other end of the rocker arm 71 is arranged to maintain the valve 57 positively opened, and for that purpose has a tappet 73 adapted to engage the outer end of the valve stem 61.

40 The high pressure cylinder 12 is similarly provided with an unloading port 80 disposed substantially diametrically opposite the discharge port 54 of said cylinder, and communicating with the inlet port 48 through an arcuate passageway 81. A spring-closed unloading valve 82 similar to the valve 57 and similarly disposed in a housing 79 controls the flow through the port 80, and is positively maintained in open position by means of a rocker arm 83 affixed to a rocker shaft 84 journaled in a valve housing section 85.

45 The unloading valve 57 of the low pressure cylinder 11 is positively operated by a cam 90 (Figs. 1, 6 and 8) in the form of a shaft journaled at its ends in the crankcase 16, and provided with tapering cam conformations or taper-

ing dwell to be described. This cam 90 is rotated at the same angular speed as the crank shaft 31 through a sprocket chain drive 91. In follower engagement with the periphery of the cam 90 is a roller 92 supported for rotation between a pair of lever arms 94 rigid with and extending substantially radially from a hub 95 splined to a shaft 96 for slidable movement therealong, and keyed to said shaft for rotation therewith. This shaft 96 is journaled in the crankcase 16.

As the cam 90 rotates, the follower roller 92 moves substantially vertically (Fig. 1), causing corresponding angular oscillatory movement of the lever arms 94, and a corresponding rotary movement of the shaft 96. The rocking movements of the shaft 96 are transmitted to the rocker shaft 72 by means of a lever arm 97 (Figs. 1 and 3) affixed to one end of the rocker shaft 72 outside the valve housing 63, and having at its free end a ball and socket connection 98 with one end of a link 100. The other end of this link 100 has a ball and socket connection 101 with the outer end of a lever arm 102 affixed outside the crankcase 16 to the shaft 96 for angular oscillation therewith.

A spring 103 in the housing 67, bearing at its ends against a radial extension of the rocker arm 71 and against a wall of said housing, serves to maintain the roller 92 constantly in follower engagement with the cam 90.

The cam 90, as shown in Figs. 8 and 14, has a cylindrical section 105 near one end, a cylindrical section 106 of smaller diameter near the other end, and an intermediate section 107 having a radial cam projection or dwell 108 merging into said end sections and progressively widening at its radially outer end along a circular arc 109 coextensive with the periphery of the larger cylindrical end section 105 as said projection approaches said larger end section. The roller 92 and the cam 90 are moved relatively axially, as described hereinafter to move said roller 92 to any selected portion of said cam according to the desired effective displacement of the cylinder 11.

As the radially outer forward side of the cam projection or dwell 108 rides underneath the follower roller 92 during the suction stroke of the piston 27, it opens the unloading valve 57, and as the rear side of said cam projection 108 passes underneath said roller, the valve 57 under the action of its spring 68 is closed. The opening and closing phases of the valve 57 relative to the cycle of the piston 27 depends on the width of the cam projection or dwell 108 at its radially outer end in the plane of the follower roller 92, and this in turn depends on the axial position of said roller with respect to the cam 90.

The unloading valve 82 of the high pressure cylinder 12 is controlled by a cam 115 journaled in the crankcase 16, and extends parallel to the cam 90, Figs. 1, 2, 4 and 6. This unloading valve 82 is disposed on the side of the vertical plane of the common center line of the two cylinders 11 and 12 opposite to the unloading valve 57 of the low pressure cylinder 11, so that the cam 115 for operating said valve 82 is disposed on the same side, and on the side of the crank shaft 31 opposite to the cam 90. This cam 115 is rotated at the same angular speed as the crank shaft 31 by means of a sprocket chain drive 116, and operates the valve 82 in a manner similar to that already described in connection with the operation of the valve 57. This operation is effected through a cam roller 117 supported on

and between a pair of lever arms 118 rigidly extending from a hub 120, which is splined to a shaft 121 for rotation therewith, and for axial movement therealong. This shaft 121 is journaled in the crankcase 16, and rigidly carries near one end outside said crankcase a crank arm 122 operating a lever arm 123 through a link 124 having ball and socket end connections with said arms. The lever arm 123 is affixed to one end of the rock shaft 84 on the outside of the valve housing 79, so that the up and down cam follower movement of the roller 117 is translated into oscillatory angular movement of said rocker shaft 84, and in turn into opening and closing movements of the escape valve 82.

The rocker shafts 72 and 84 project outside their respective housings 63 and 79 in opposite directions and towards opposite ends of the crankcase 16 in position to receive their transmissions from the shafts 96 and 121 to the unloading valves 57 and 82. The projecting parts of these rocker shafts 72 and 84 are supported in bearings 125 and 126 respectively rigid with respective housing sections 67 and 85. To prevent leakage of air through the bearing 126 associated with the high pressure cylinder it is provided with a stuffing box 126a (Fig. 3) in the end nearest the arm 123 and the opposite end of said bearing is closed.

The two cams 90 and 115 are similar in construction, and have similar cross-sections at common transverse planes, but since the two cranks 30 and 33 are 180° apart on the crank shaft 31, said cams are also disposed 180° apart, so that while the valve opening projection on one cam extends upwardly, the corresponding projection on the other cam extends downwardly as shown in Fig. 1. With this arrangement of the two cams 90 and 115, it is possible to rotate the crank shaft 31 in either direction without the effective displacements of the cylinders being altered with any adjustment of the control lever 150 to be described.

For moving the follower rollers 92 and 117 along their respective cams 90 and 115, there is provided a pair of parallel guide rods 130 and 131 (Figs. 1 and 4 to 7), fixed at one end at 132 and 133 respectively to an end wall of the crankcase 16, and extending through the opposite end wall of said crankcase and to a control device 134 to be described. At the other end, these guide rods 130 and 131 are secured to the respective posts 135 and 136 extending up from and secured to the base 16b. Embracing the guide rods 130 and 131 with a slidable fit are a pair of long sleeves 137 and 138 respectively extending through an end wall of the crankcase 16, and terminating at its outer end near the control device 134. At the inner end in the crankcase, the sleeve 137 has rigid therewith fork 140 having arcuate fingers extending into a circumferential groove 141 in the periphery of the hub 95 supporting the cam roller 92. The sleeve 138 is similarly provided in the crankcase 16 with a fork 142 having arcuate fingers extending into a circumferential groove 143 in the periphery of the hub 120 supporting the cam roller 117. With this construction, the movement of the sleeves 137 and 138 axially along their respective guide rods 130 and 131 causes movement of the cam rollers 92 and 117 along their respective cams 90 and 115 without interfering with radial oscillatory movement of the hubs 95 and 120.

The sleeves 137 and 138 are axially moved in unison along their guide rods 130 and 131 and

into selected position with respect to their respective cams 90 and 115 by means of the control device 134. This control device 134 which is one form of the invention comprises a bracket frame 144 secured to the base 165 and having opposed stanchions 145 and 146. Rigid with the upper end of one of the stanchions 146 is a sector 147 provided with a series of notches 148 to assist in holding the cam rollers 92 and 117 in their adjusted positions according to effective displacement desired by the cylinders. An upstanding lever control handle 150 is secured at its lower end to a rocker shaft 151 which is supported by the frame stanchions 145 and 146. A sleeve 152, supported on that portion of shaft 151 located between the stanchions 146 and 147, has two parallel arms 153 and 154. This sleeve 152 is secured to the shaft 151 and its arms 153 and 154 are disposed in the longitudinal plane of the control handle 150 (Fig. 5). The arms 153 and 154 have link connections at their lower ends with the slide sleeves 137 and 138 respectively. The link connections for the arm 153 includes a link 155 pivotally connected at its ends with the lower end of the arm 153 and the slide sleeve 137, and the link connection with the arm 154 includes a link 156 pivotally connected at its ends with the lower end of the arm 154 and the slide sleeve 138.

The control handle 150 is held in any selected position with respect to the notched periphery of the sector 147 so as to maintain the cam rollers 92 and 117 in their adjusted positions. This locking of the handle 150 is done by means of a detent 160 which is slidable in a bearing 161 affixed to said handle, and which is normally pressed into handle locking position in any selected notch 148 by a coil spring 162. The detent 160 and notches 148 are so formed that the handle 150 can readily be moved into any selected position by the detent riding over the teeth and dropping into any one of the notches. This angular movement of the control handle 150 causes angular movement of the two parallel arms 153 and corresponding endwise movement of the two slide sleeves 137 and 138 along their guide rods 130 and 131. This movement of the slide sleeves 137 and 138 is transmitted to the roller supporting sleeves or hubs 95 and 120, so that the follower rollers 92 and 117 are moved along their respective cams 90 and 115, and in selected position with respect thereto, as determined by the position of the control handle 150.

The compressor cylinders 11 and 12 are designed for the particular final pressure against which the compressor is intended to do most of its work. Assuming that the compressor is intended to operate normally against a final pressure of 220 lbs. gage at sea level, then the displacement of the low pressure cylinder 11 should be about four times that of the high pressure cylinder 12. Assuming that the pistons 27 and 32 have the same stroke, the relative capacities of the two stages would vary as the square of the diameters of the cylinders, the diameter of the low pressure cylinder 11 would be about twice that of the high pressure cylinder 12, to afford a four to one displacement ratio between the two cylinders 11 and 12. In the present invention the high pressure cylinder is made of slightly larger diameter than above stated but the displacement ratio of 4 to 1 is maintained by giving the high pressure piston 32 a shorter stroke than that of the low pressure cylinder. With the dimensional proportions disclosed, the

low pressure cylinder 11 will compress the air from atmospheric at sea level to about 44.3 lbs. gage, which corresponds to a ratio of compression of four, and the second cylinder will compress the air from 44.3 to 220 lbs. gage, which also corresponds to a ratio of compression of four.

If it is desired, for example, to operate the compressor at 100% capacity, the control handle 150 is set to bring the follower rollers 92 and 117 into the position shown in Fig. 14, in which said rollers engage the smaller cylindrical end sections of said cams respectively. In this position, the cam rollers 92 and 117 will be in their lowermost position, and will remain there during the operation of the compressor, so that the unloading valves 57 and 82 will remain closed during the entire operating cycle unless opened by suction. When the control handle 150 is set to position the follower rollers 92 and 117 on the intermediate sections of the respective cams 90 and 115 carrying the radial valve opening projections, the valves 57 and 82 will be positively held open during a selected phase of the suction stroke of the piston and a portion of the compression stroke thereof.

The cam then permits the closing of the unloading valve for the remainder of the compression stroke of the piston. If, for example, it is desired to pump to the same pressure but only one-third the volume of air which is pumped at full capacity, then the control lever 150 is set to position the follower rollers 92 and 117 on their respective cams 90 and 115, so that the unloading valves 57 and 82 are positively held open until the pistons have completed about two-thirds of their compression strokes.

While the unloading valves 57 and 82 are open during the compression strokes in their respective cylinders 11 and 12, no air is compressed, but is discharged at approximately inlet pressure through said valves and into the inlet manifolds and pipes. The compression strokes in the cylinders 11 and 12 are thereby rendered ineffective for the portions thereof during which said unloading valves 57 and 82 are open. The effective portions of the compression strokes do not begin until these unloading valves 57 and 82 are closed.

During the suction strokes, the air which has been compressed in the clearance spaces during the previous compression strokes, is expanded against the pistons, so that the work of compressing this air is not lost but returned to the pistons. When this air has been expanded to a pressure slightly below that of the air in the inlet pipe, the corresponding inlet valves 42 and 50 are automatically opened against their spring means by the differences in pressure on opposite sides of said valves. The unloading valves 57 and 82 are not opened until after these inlet valves 42 and 50 are open, so that these unloading valves do not interrupt the expansion of the clearance air against the pistons. These unloading valves 57 and 82 are desirably positively opened by the mechanical device shown, but as far as certain aspects of the invention are concerned, these valves may be initially opened automatically by the differences in pressures on opposite sides of said valves as in the case of the inlet valves 42 and 50. The mechanical means will then operate only to positively maintain the unloading valves 57 and 82 open until their corresponding pistons have reached the desired points in their compression strokes.

The effective displacement of the two cylinders

11 and 12 will be simultaneously adjusted proportionately by the adjusting operations described, so that their relative displacements will be maintained substantially constant, irrespective of the setting of the control handle 150. 5 Therefore, as long as the compressor is working against the final pressure for which its cylinders were designed, the ratio of compression in each cylinder remains substantially constant, and the ratios of compression of the two cylinders will be substantially equal, thereby assuring substantial equalization of work and heat generation in the two cylinders 11 and 12 for all settings of the control handle 150.

When the control handle 150 is set to position the rollers 92 and 117 in cam follower relationship with respect to the larger cylindrical end sections of their respective cams 90 and 115, as shown in Fig. 9, the unloading valves 57 and 82 will be maintained continuously open, and the compressor will be operating at zero capacity.

It will be understood that since the air enters the low pressure cylinder from the atmosphere, and the air enters the high pressure cylinder from the intercooler the air entering both cylinders is relatively cool. Under all conditions except when the compressor is working at full capacity some of the air taken into the cylinders on the suction stroke of the pistons is expelled therefrom on the compression strokes of the pistons. Thus there is produced a circulation of relatively cool air through the cylinders, which serves to cool them internally and effectively.

It may be desirable to maintain a substantially constant predetermined pressure in a receiver. To this end, an automatic control may be provided which is settable to the pressure required. This arrangement includes a pipe 166, Fig. 15, through which compressed air from the receiver tank 53 passes into a cylinder 166a. This cylinder 166a has therein a piston 167 which is urged towards the right by a spring 168. As the pressure increases in the receiver 53 the piston 167 is forced towards the left in the cylinder 166a until it balances the pressure of the spring 168. A rod 169 connected to the piston 167 and to a lever arm 154 shifts the cam rollers 92 and 117 to reduce the effective displacement of the compressor until when the pressure reaches the maximum desired, no air is delivered. The constant at which the pressure is to be maintained may be varied by regulating the pressure of the spring 168. This may be accomplished by a cap 166b threaded on the end of the cylinder 166a and engaging one end of the spring 168.

Although the invention is shown applied to a compressor of the multi-stage type, as far as certain aspects of the invention are concerned, this may be applied to a single-stage compressor.

Also, as far as certain aspects of the invention are concerned, instead of employing an unloading valve separate from the inlet valve, the inlet valve may be employed as an unloading valve, opening by suction and held open mechanically substantially as described in connection with the unloading valves 57 and 82, or the inlet valve shown may be simply omitted. The unloading valve can act as an automatic inlet valve especially if its spring is not too stiff so that the inlet valve shown is really not necessary though perhaps desirable.

Moreover, as far as certain aspects of the invention are concerned, instead of varying the two effective displacements simultaneously and proportionately, these may be varied separately inde-

pendently of each other, as by providing a separate control handle for each of the rollers 92 and 117 instead of the single handle shown in Fig. 5.

In Fig. 15, the invention is diagrammatically shown applied to a two-stage compressor with means to prevent warm air rejected through the unloading valve 82 of the high pressure cylinder 12 from being again drawn into this cylinder before it is cooled in the intercooler 13. A check valve 164 permits air to flow from the intercooler 13 only towards the high pressure cylinder 12. Warm air expelled through the unloading valves 82 of the high pressure cylinder 12 is caused to flow through check valve 165 into the hot end of the intercooler 13. In the intercooler 13, the air is reduced approximately to the intake temperature at the inlet of the low pressure cylinder 11. Only cool air from the cool end of the intercooler 13 can enter the high pressure cylinder 12.

In Fig. 16 is shown a multi-cylinder two-stage compressor 10 provided with a single intercooler 175. The outlet pipes 176 of the two low pressure cylinders 11 merge into a single pipe 177 leading to the inlet of the intercooler 175. The outlet of the intercooler 175 has two parallel branch connections 178 provided with respective check valves 164, and leading to the inlets of the high pressure cylinders 12 respectively. The discharge sides of these high pressure cylinders 12 connect through pipes 180 into a common outlet 181. The rejected air discharged through the unloading valves 82 of the high pressure cylinders 12 is returned through the check valves 165 and back into the intercooler 175, in the manner already described in connection with the arrangement of Fig. 15.

In Fig. 17 is shown a multi-cylinder two-stage compressor 10 similar to those shown in Fig. 16, the only differences being that there are two intercoolers 185, one for each compressor or, in other words, one for each set of cylinders.

In Fig. 18 is shown diagrammatically the present invention applied to a double-acting compressor 190. This compressor 190 is shown comprising a cylinder 191 having a piston therein operated from a crank shaft 193, through a cross-head 194, a connecting rod 195 between one side of said cross-head and a crank 196 on said crank shaft, and a piston rod 197 between the other side of said cross-head and said piston. Heads or water jackets 198 are provided at each end of the cylinder 191 and inlet valves 200 and discharge valves 201. Each of the inlet ports for these inlet valves 200 connect into a chamber 202 having a filter 203 on its intake side. The outlet ports controlled by the discharge valves 201 connect into a common outlet 204 in the usual manner.

For varying the effective displacement of the compressor 190 or in other words, the effective stroke thereof there are provided two unloading valves 205 one at each working end of the cylinder 191, each valve operating in a port communicating with the inlet of the cylinder through the inlet chamber 202. Each unloading valve 205 may be of the type similar to that shown in connection with the unloading valve 57 of Figs. 1-14, but is operated from a bell crank 206 pivoted at 207, and having one arm 208 engaging the free end of the stem 210 to valve 205 to open the latter against the action of a spring, not shown. Each bell-crank 206 has another arm 211 carrying a roller 212 in follower engagement with a cam 213. The cam 213 shaped like the

cam 90 is operated from the crank shaft 193 through a chain and sprocket drive 214, and is of shaft-like construction and designed to open positively the escape valves 205 at selected phases with respect to the corresponding strokes, and maintain them open for selected periods during their corresponding compression strokes according to the setting of the cam 213. This cam 213 is not stationary as the cam 90 but mounted for axial adjusting movement, and when axially moved, it will change the phases during which the unloading valves 205 are opened and closed so that the effective compression strokes of the piston 192 are changed, while maintaining said effective strokes on opposite sides of said piston substantially equal. It will be understood that in this form of the invention a single cam is used to operate two unloading valves alternately at 180° intervals of rotation.

I have described what I believe to be the best embodiments of my invention. I do not wish, however, to be confined to the embodiments shown, but what I desire to cover by Letters Patent is set forth in the appended claims.

What I claim is:

1. A multi-stage compressor comprising at least two cylinder parts, a piston reciprocable in each of said cylinder parts, and means for selectively varying the effective volumetric displacement of each of said cylinder parts, comprising an unloading valve in each of said parts, adapted when open to prevent compression in the corresponding cylinder part, mechanical means free from electric or fluid operation, for positively maintaining said valve open during a selected portion of the compression stroke of the corresponding piston, and means for varying the phase at which each of said valves is opened with respect to the stroke cycle of its corresponding piston, said means for changing the effective volumetric displacements of the cylinder parts comprising a plurality of cams corresponding to the compression cylinders in the compressor, means for rotating said cams at predetermined relative angular rates, each of said cams being in the form of a shaft having a valve opening projection progressively changing lengthwise of said cam, a follower roller in engagement with each of said cams, a mechanical transmission free from mechanical or fluid operation between each of said rollers and a corresponding unloading valve for maintaining said valve open during a selected part of the compression stroke of the corresponding piston, and means for moving all of said followers in unison along their corresponding cams for simultaneously varying the phase relationship between the operating sections of said cams and the stroke cycles of the corresponding pistons.

2. A multi-stage compressor comprising two cylinders disposed alongside of each other, a piston reciprocable in each of said cylinders, a common crankcase for said cylinders, a crank shaft in said crankcase for operating said pistons, and means for selectively varying the effective volumetric displacement of each of said cylinders, comprising an unloading valve at the working end of each cylinder adapted when open to prevent the pressure from building up in said working end, said unloading valves being disposed on opposite sides of the common line of the two cylinders, a pair of parallel cams journalled for rotation in said crankcase and disposed on opposite sides of said crank shaft, each of said cams being in the form of a shaft having a valve open-

ing conformation progressively changing lengthwise of said cams, means for driving said cams from said crank shaft, a follower in engagement with each of said cams, a transmission between each of said followers and the corresponding unloading valve on the same side of the common center line of the two cylinders, for maintaining said valve open during a selected part of the compression stroke of the corresponding piston, and means for moving said followers along their corresponding cams for varying the phase relationship between the operative sections of said cams and the stroke cycles of their corresponding pistons.

3. A multi-stage compressor as described in claim 2, in which the valve opening conformations on said cams extend 180° apart, whereby said crank shaft may be rotated in either direction without affecting the effective displacement of the cylinders.

4. A compressor as described in claim 2, including a control member, and means operable in response to said control member for moving said followers in unison along their respective cams.

5. A multi-stage compressor, comprising at least two cylinder parts, a piston reciprocable in each of said cylinder parts, a control member, and means operable in accordance with the setting of said control member for varying the effective volumetric displacement of each of said cylinder parts, said means being operable to permit operation of said compressor in either direction without substantially affecting the volumetric displacement of said cylinder parts as determined by the setting of said control member.

6. A multi-stage compressor as described in claim 5, which comprises a crank shaft for operating said pistons, and in which the means for varying the effective displacement of the cylinder parts includes an unloading valve for each cylinder part, and a cam for operating each of said valves driven from said crank shaft, said cams being arranged with their corresponding dwells extending 180° apart, to permit the rotation of the crank shaft in either direction without varying the effective displacement of said cylinder parts for a particular setting of said control member.

7. A compressor comprising a cylinder, a piston reciprocable therein, an inlet port on one side of said cylinder at its working end, an inlet valve for said port, and means for selectively varying the effective volumetric displacement of said cylinder, and comprising an unloading port at the working end of said cylinder, a passageway around said cylinder establishing communication between said ports, an unloading valve in said unloading port adapted when open to prevent the pressure from building up in said working end, mechanical means for positively maintaining said unloading valve open during the forepart of the compression stroke, and means for selectively varying the opening and closing phases of said unloading valve relative to the stroke cycle of said piston.

8. A compressor comprising a cylinder, a piston reciprocable therein, an inlet port on one side of said cylinder at its working end, an inlet valve for said port, and means for selectively varying the effective volumetric displacement of said cylinder, and comprising an unloading port at the working end of said cylinder, a passageway establishing communication between said ports, an unloading valve in said unloading port adapted

when open to prevent the pressure from building up in said working end, means for maintaining said unloading valve open during the forepart of the compression stroke, and means for selectively varying the closing phase of said unloading valve relative to the compression stroke of said piston.

9. A compressor comprising a cylinder affording a clearance space, a piston reciprocable therein, an inlet valve at the closed end of said cylinder operable in accordance with the difference in pressures on opposite sides thereof, and means for varying the effective volumetric displacement of said compressor, comprising an unloading valve at the closed end of said cylinder separate from said inlet valve and adapted when open to prevent the compression of air in the cylinder, said valves being disposed in respective ports communicating with each other, means whereby said unloading valve is opened during the suction stroke but not before said inlet valve has been opened, mechanical means free from fluid or electric operation and actuated in synchronism with the reciprocation of said piston for positively maintaining said unloading valve open during the forepart of the compression stroke, said latter means being mechanically releasable at a selected phase relative to the compression stroke cycle of the piston to permit closing of said unloading valve and the compression and delivery of compressed air during the remainder of the compression stroke, and means for varying the phase at which said last mentioned valve maintaining means is released, to vary the effective volumetric displacement of said compressor.

10. A compressor as described in claim 9, in which the position of opening of the unloading valve with reference to the beginning of the suction stroke is substantially the same as the position of the closing of said unloading valve with reference to the end of the compression stroke regardless of operation of said phase varying means.

11. A multi-stage compressor comprising at least two cylinder parts, a piston reciprocable in each of said cylinder parts, and means for varying the effective volumetric displacement of each of said cylinder parts, comprising an unloading valve in each of said parts, adapted when open to prevent compression in the corresponding cylinder part, a plurality of cams corresponding to the number of cylinder parts in the compressor, a mechanical transmission free from electric or fluid operation between each of said cams and a corresponding unloading valve for maintaining said valve open during a selected part

of the compression stroke of the corresponding piston, and means for simultaneously varying the phase relationship between the operative sections of said cams and the stroke cycles of the corresponding pistons.

12. A compressor comprising a cylinder, a piston reciprocable therein, means for varying the effective volumetric displacement of said compressor, including an unloading valve at the closed end of said cylinder, means for opening said valve during the suction stroke and closing said valve during the compression stroke, the phase in the suction stroke when said valve opens as measured from the end of the suction stroke corresponding to the phase in the compression stroke when said valve closes as measured from the beginning of the compression stroke, and means for varying the phase at which said unloading valve is opened and closed, while maintaining correspondence between the opening phase of the valve during the suction stroke and closing of the valve during the compression stroke.

13. A multi-stage compressor comprising at least two cylinders, a crankcase, a crankshaft in said crankcase, a piston reciprocable in each of said cylinders, and means for selectively varying the effective volumetric displacement of each of said cylinders comprising an unloading valve in each of said cylinders, adapted when open to prevent compression in the corresponding cylinder, a plurality of cams corresponding to the number of cylinders in the compressor and mounted in said crankcase, means for driving said cams from said crankshaft, a mechanical transmission free from mechanical or fluid operation between each of said cams and a corresponding unloading valve for maintaining said valve open during a selected part of the compression stroke of the corresponding piston, and means for varying the phase relationship between each cam and the stroke cycle of the corresponding piston.
